UNITED STATES PATENT OFFICE

ALFRED OBERLE, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR HEATING PETROLEUM OIL

Application filed April 19, 1923, Serial No. 633,099. Renewed September 14, 1928.

This invention relates to improvements in a process for heating petroleum oil, and refers more particularly to a process in which oils are continuously treated under pressure and temperature conditions to produce conversion of the oils into oils of a lower boiling point having the characteristics of gasoline.

Among the objects of the invention are to provide a process in which the oil is introduced and preheated in a rectifier and subsequent thereto, being subjected to conversion temperature, the vapors evolved being dephlegmated and passed through the incoming charging stock in order to relieve therefrom objectionable high boiling point fractions, and to improve the quality of the resulting distillate.

The single figure is a diagrammatic side elevational view of the apparatus, with parts 20 in section.

At 1 is shown a furnace in which is mounted a still 2 having positioned thereabove a rectifier or heat exchanger 3. The oil is introduced through the pipe 4, regulated by a valve 5, and is charged by means of a pump 6 through a line 7 regulated by a valve 8 to the heat exchanger 3 where it is permitted to collect, the level in the heat exchanger being regulated by an overflow pipe 9 controlled by a valve 10. This overflow pipe terminates in the heat interchanger near the bottom, thus the oil drawn from the chamber is taken from the lower portion thereof. This oil flows over, and is introduced into the still 2 which is also positioned in the furnace 1, and is subjected to the hottest combustion gases which are supplied by means of gas burners one of which is shown at 11.

40 This still may take the form of a header type boiler having headers at the opposite ends of the furnace and connecting tubes in place of the cylindrical still shown. The ends of the still 2 are removed for cleaning purposes. In the still, the oil is subjected to a conversion temperature, the vapors evolved passing off through the vapor line 12 to a dephlegmator 13. The greater part of the vapor line 12 is positioned in the stack 14, thus the vapors are introduced to the

dephlegmating column substantially at the temperatures at which they left the still.

The dephlegmator shown, consists of an upper and lower header 15 and 16 respectively, connected by tubes 17. A cooling medium is passed through the dephlegmator proceeding from one header to the other, and being introduced either at the top or bottom through the pipe 19 or 18 controlled by suitable valves either to flow in an opposed direction to the vapors which are circulated therethrough, or in the same direction as the vapors which pass downwardly about the tubes, and which are directed by the spiral plate 20.

60 It is understood also, that this type of dephlegmator may be replaced by any other suitable construction which will serve to properly dephlegmate the vapors. The cooling medium used to produce dephlegmating action may be a cool oil, water or other liquid mediums.

70 The hydrocarbons after being subjected to the dephlegmating action of the dephlegmator 13 pass out through the line 21 controlled by a valve 22 and are introduced into the bottom of the heat exchanger or rectifier 3 through the perforated pipe 23. In this manner, they are caused to percolate up through the oil body maintained in the 75 chamber 3, being subjected in their passage through this body to the rectifying action of the relatively cool charging stock. In addition to the rectifying effect of this oil body, there is the advantage of the heat exchange which takes place between the vapors and oil body transferring considerable heat to the incoming charging stock.

85 During this percolation of the vaporous hydrocarbons through the oil maintained in the chamber 3, the oil is also being heated due to the fact that it is positioned in the furnace and during heating is kept in a turbulent condition, due to the passage of the oil vapors therethrough. During this percolation of the vapors, there is relieved from the charging stock considerable light fractions or cuts which pass off with the rectified vapors through the vapor line 24 90 regulated by a valve 25 to the water con-

denser 26 where the vapors are subjected to a final condensing action. Passing from the condenser coil, the oil is discharged through the pipe 27 in which is interposed a valve 28, into the receiving tank 29. This receiving tank is equipped with a liquid level gauge 30, a pressure relief valve 31, a pressure gauge 32, and a liquid drawoff line 33 controlled by a valve 34. The still 2 is equipped 10 with a residual drawoff line 35, regulated by a valve 36 whereby the unvaporized liquid oil constituents and residual substance may be withdrawn from the still.

Try-cocks 37 are tapped into the end of 15 the still at different levels in order to ascertain the height of the liquid maintained therein during reaction.

The advantages of the process are principally in the introduction of oil to the heat 20 exchanger, where it is first preheated due to the positioning of the exchanger in the furnace, and secondly, to the percolation of the hot dephlegmated vapors therethrough. Besides the advantage of preheating the raw 25 oil, this percolation of the vapors through the charging stock serves to relieve the vapors of certain objectionable fractions which would normally pass over to the receiver.

This oil body in the heat exchanger or 30 rectifier, also serves to absorb gases and hydrocarbon fractions, which would naturally be lost during the subsequent treatment of the distillate to produce refined gasoline.

During treatment of the oil, the apparatus 35 is preferably operated under known superatmospheric pressure, regulated according to the character of the oil treated through the medium of valve 31 which maintains a substantially uniform vapor pressure 40 upon the apparatus.

The process is economical in that the heat utilized to convert the oil is efficiently used, due to the connecting line within the furnace structure.

45 By treating gas oil of 32° Baumé to temperatures ranging from 700° to 900° F., a yield of from 50% to 70% of high grade distillate may be obtained, the distillate having a gravity of from 48° to 52° Baumé, and 50 yielding good quality gasoline of new Navy specification. The distillate is conspicuous in its low content of unsaturated hydrocarbons.

I claim as my invention:

55 1. A process of oil conversion, consisting in introducing the oil to a pool positioned in a heating means, and there maintaining the oil at a controlled level, passing the oil thence to a cracking zone also positioned in 60 the heating means, and there raising the oil to a cracking temperature, in passing vapors evolved from the oil heated in said cracking zone to a dephlegmator, in subjecting the vapors in said dephlegmator to dephlegmation 65 by cooling said dephlegmator, in thereafter

returning the dephlegmated hydrocarbons withdrawn from said dephlegmator to the oil maintained in the initial pool, and in subjecting uncondensed vapors rising from said initial pool to final condensation.

2. A process of oil conversion, consisting in initially introducing the oil to a pool positioned in a heating means, and there maintaining the oil at a controlled level, in passing the oil from said pool to and heating it to a cracking temperature in a cracking zone also positioned in said heating means, in passing vapors evolved from the oil heated in said cracking zone to a dephlegmator, in causing dephlegmation of the vapors in said dephlegmator, in returning the condensate resulting from the dephlegmation and dephlegmated vapors from said dephlegmator to said pool, in causing the dephlegmated vapors to percolate through the oil in said pool and in thereafter subjecting the uncondensed vapors to final condensation, and in maintaining a superatmospheric pressure on the oil undergoing conversion.

3. In an apparatus for cracking oil, the combination with initial and secondary zones for raising the temperature of the oil to a conversion condition positioned in a source of heat, means for transferring the liquid oil from the initial to the secondary zone and for maintaining a liquid level in the initial zone, a dephlegmator, means for transferring vapors evolved from the oil which has been raised to a conversion temperature to said dephlegmator, means for circulating a cooling medium through said dephlegmator, means for passing the condensate and vapors from said dephlegmator to said initial heating zone, means for causing the vapors to percolate through the oil body in said initial heating zone, means for condensing vapors withdrawn from said initial heating zone, and means for maintaining a controlled pressure on the oil undergoing treatment.

4. An oil cracking process which comprises preheating the oil in an initial heating zone, passing the preheated oil to a second heating zone and subjecting the same to cracking temperature therein, removing vapors from said second heating zone and subjecting the same to dephlegmation, passing the dephlegmated vapors and condensate formed in the dephlegmation to said initial heating zone, and removing and condensing vapors from said initial heating zone.

5. An oil cracking process which comprises preheating the oil in an initial heating zone, passing the preheated oil to a second heating zone and subjecting the same to cracking temperature therein, removing vapors from said second heating zone and subjecting the same to dephlegmation, passing

the dephlegmated vapors through the oil
in said initial heating zone, combining con-
densate formed in the dephlegmation with
the oil in said initial heating zone, and re-
moving and condensing vapors from said
initial heating zone.
